Inventor:

George R. Dobbins.

United States Patent Office.

GEORGE R. DOBBINS, OF LOWELL, MASSACHUSETTS.

Letters Patent No. 81,851, dated August 25, 1868.

IMPROVEMENT IN BOILER-FLUE CLEANERS.

The Schedule referred to in these Letters Patent and making part of the same.

TO ALL WHOM IT MAY CONCERN:

Be it known that I, GEORGE R. DOBBINS, of Lowell, in the county of Middlesex, and State of Massachusetts, have invented new and useful Improvements in a Device for Cleaning Boiler-Flues; and I do hereby declare that the following is a full and exact description thereof, reference being had to the accompanying drawings, and to the letters of reference marked thereon.

The nature of my invention consists in a device for cleaning boiler-flues, which is provided with a spreader whereby the steam, in passing through the device into the flue, is forced against the entire inner surface, whereby to remove all obstacles, thus cleaning the same.

To enable others skilled in the art to make and use my invention, I will proceed to describe its construction and operation.

Figure 1 represents a plan of my improved device for cleaning boiler-flues.

Figure 2 represents a longitudinal section of the same.

Figure 3 represents an end elevation of the flue-end, with parts removed, showing the construction of the same.

Similar letters in the different figures indicate corresponding parts.

I construct my improved device in two parts, *a* representing the end to be connected and secured to a suitable pipe, which may be made of rubber, leather, or metal, as the user may desire, *b* the flange, and *c* the spreader, this spreader *c* being in a cone-shape form, its apex secured by a screw, or its equivalent, to the rib *d*, the rib *d* connecting with the flue-end *e* of the device. The base of the spreader *c*, when in position, being minus flush with the flue-end *e*, its diameter being less than the diameter of the flue-end *e*, thus leaving a space between the same.

Operation.

The device, being thus constructed, and its several parts arranged as described, is then connected and secured to a suitable pipe leading from the boiler, or any of its appendages connected thereto. The flue-end *e* is then placed into the flue "to be cleaned" up to the flange *b*, this end *e* being made enough smaller than the flue, to overcome the expansion of the same caused by the steam when passing through the same.

The steam is then let into the pipe, which, by its pressure, passes through the same, coming in contact with the spreader *c*, which, being made angular, offers no resistance, nor impeding the progress of the steam, conveying it to the opening, as seen in figs. 2 and 3, at P P, where it enters the flue, the whole pressure and force of the steam coming in contact with the inner surface of the same, which, by its great force centred to and on the inside of the flues, removes all obstructions, and forces the same through and out of the other end of the same, thus completely cleaning the flues, leaving them as free from obstructions as when new.

What I claim as my invention, and desire to secure by Letters Patent, is—

The arrangement of the spreader *c*, flue-end *e*, pipe *a*, flange *b*, and rib *d*, when constructed as herein set forth:
